UNITED STATES PATENT OFFICE.

JOSEPH TAYLOR, OF STOCKPORT, ENGLAND, ASSIGNOR TO HAT MANUFACTURERS SUPPLY CO. LTD., OF STOCKPORT, ENGLAND.

HAT.

No. 818,814.

Specification of Letters Patent.

Patented April 17, 1906.

Application filed October 18, 1905. Serial No. 283,279.

To all whom it may concern:

Be it known that I, JOSEPH TAYLOR, a subject of the King of Great Britain and Ireland, and a resident of Stockport, county of Lancaster, England, have invented certain new and useful Improvements in Hats, of which the following is a specification.

My invention is more particularly designed as an improvement on the construction of hats forming the subject of Wildman's patent, No. 574,697, dated January 5, 1897, and in which there is provided a band of elastic material within the hat-sweat with free ends by means of which the tension of the elastic band may be varied to vary or adapt the opening within the hat-sweat for a comfortable fit on the wearer's head.

I have found that the prior construction referred to is subject to the objection that the user is liable to make the tension of the elastic band too great, with the result that on wearing the hat the part of the elastic band in front of the forehead is apt to make a mark on the wearer's forehead.

My present invention consists of means for overcoming this objection, and this I do by so securing the elastic band, whether actually in one piece or two pieces, to the inelastic part of the hat sweat or lining—that is, either the pad or leather—that if there is any portion of elastic left in front of the forehead of the wearer behind the hat-sweat that portion of such band will not be stretched by the tying up of the free ends.

In the accompanying drawings, Figure 1 is a sectional view of a hat provided with my improvement. Fig. 2 is an under side view of the hat, and Fig. 3 is an enlarged perspective view of the hat-sweat and elastic band. Fig. 4 is a perspective view illustrating a modification.

In the drawings, A is the hat, which may be of straw, felt, or other suitable material.

B represents the leather of the hat-sweat, and C represents the pad or foundation stitched or otherwise secured to the leather and by which the hat-sweat may be secured

in any usual or suitable way to the hat by stitching or otherwise.

D is the elastic band, which is back of the hat-sweat and which is preferably threaded through a folded strip of material E, secured to or forming part of the pad or foundation. This elastic band may be made of either one or two pieces and at the back of the hat has free ends d d, which may be tied together to give any desired tension, the free ends being indicated tied up by dotted lines in Fig. 1. At a point which should be about opposite to the temples of the wearer's head I secure this band D by clamps F, Fig. 3, or other suitable means to the inelastic pad or foundation or to the leather of the hat itself, so that in front of the forehead of the wearer there may be no stretchable elastic band—that is to say, stretchable by the tightening of the free ends d d, already described. For convenience of manufacture, however, the elastic band may extend all around the hat, and by reason of the clamps F or other suitable securing means the tightening up of the free ends of the band D will not stretch that portion of it which lies between the clamps or other securing means—that is to say, in front of the wearer's forehead. As an example of other securing means to attach the elastic cord or band fixedly in relation to the hat-sweat at points opposite the wearer's temple I may mention stitching, as indicated at F' in Fig. 4.

I claim as my invention—

A hat provided with a sweat, an elastic band behind the sweat and having free ends toward the back of the hat, with means fixedly securing the elastic band to the hat-sweat at points near the wearer's temples, for the purpose described.

In testimony whereof I have signed my name to this specification in the presence of two subscribing witnesses.

JOSEPH TAYLOR
